UNITED STATES PATENT OFFICE.

FREDERICK A. DAVIES AND CARL L. ROGERS, OF WILKINSBURG, PENNSYLVANIA.

EAR BASIN.

Application filed August 26, 1922. Serial No. 584,438.

To all whom it may concern:

Be it known that we, FREDERICK A. DAVIES and CARL L. ROGERS, both citizens of the United States, residing at Wilkinsburg, 5 in the county of Allegheny and State of Pennsylvania, have invented new and useful Improvements in Ear Basins, of which the following is a specification.

This invention relates to receiving devices, and more particularly to what we term an ear basin.

One of the main objects of the invention is to provide a device of simple and efficient construction which may be readily applied 15 and held in position on the patient's ear so as to permit freedom of the physician's hands. A further object is to provide a device which, when applied, will serve to catch the overflow from the patient's ear 20 when the ear is irrigated, permitting the washing solution to be discharged into a suitable container while retaining the solid substances which are removed from the ear to permit the latter to be examined by the 25 physician. Further objects will appear from the detailed description.

In the drawings:—

Figure 1 is a perspective end view of the device;

30 Figure 2 is a side view;

Figure 3 is a central longitudinal section through the device;

Figure 4 is an inner end view of the device, the method of use being indicated.

35 The device includes a troughlike basin or receptacle 1 formed of sheet metal or any other suitable material, bottom 2 of which is inclined downwardly from the outer end wall 3 toward the inner end wall 4. Adjacent to the inner end wall 4 a nipple 5 is secured through bottom 2, this nipple being provided at its upper end with a perforated strainer 6 of substantially hemi-spherical shape which fits snugly against bottom 2. 40 At its lower end the nipple is provided with an enlargement 7 which is adapted for insertion into the end portion of a rubber tube 8 by means of which the liquid flowing into receptacle 1 is discharged into a suitable container.

45 For securing receptacle 1 in position for use we provide a bail 9 of substantially U-shape, the arms 10 of which are slidably through U-shaped brackets 11 secured to the 50 side walls of receptacle 1 adjacent to inner

end wall 4. Each arm 10 is provided in its outer portion with a series of notches 12 which are adapted to engage with the arms of brackets 11 for securing the bail in adjustment. To facilitate adjustment of the bail, each arm 10 is provided at its lower end with a ring 13. By forcing the rings toward each other the arms 10 are disengaged from brackets 11 thus permitting ready adjustment of bail 9, it being understood that the bail possesses resiliency and that the arms 10 are forced in opposite directions away from each other. End plate 4 is provided with a central recess or cutout 4^a which is disposed in alignment with an element 9^a of substantially semicircular shape forming the upper portion of bail 9. In practice bail 9 is moved upwardly through brackets 11 so as to permit the bail to be readily placed over the ear, after which basin 1 is adjusted so that the cutout 4^a fits about the cartilage at the lower portion of the ear in rear of the ear lobe, the ear lobe extending downwardly over cutout 4^a so as to cover the same; as indicated 75 in Fig. 4. With the device in the position described, end plate 4^a rests against the jaw of the patient, this end plate and the bail 9 being both inclined upwardly and inwardly toward the side of the patient's head, 80 as illustrated in Figures 2 and 3, so as to be held in substantially the position illustrated in Figures 2 and 3. When the ear is irrigated, the solution used and the materials removed from the ear will be discharged 85 into basin 1, the solution flowing through strainer 6, nipple 5 and tube 8. The solid particles of materials removed from the ear will remain in basin 1 so as to permit the same to be examined by the physician at 90 his leisure. This provides a very simple and efficient device which may be readily produced at small cost and, when applied, permits absolute freedom of use of both 95 hands of the physician, which is an important consideration in devices of this sort.

What we claim is:—

1. In a device of the character described, a receptacle adapted to fit behind and about the lower portion of a person's ear, and a member adjustably secured to the receptacle and adapted to fit about the upper portion of the ear and co-operating with said receptacle for holding the same in position upon and about the ear.

2. In a device of the character described, a receptacle having one end wall shaped and adapted to engage behind and about the lower portion of a person's ear, and a member adjustably secured to the receptacle adjacent to said end wall and adapted to engage over and about the upper portion of the ear.

3. In a device of the character described, a troughlike receptacle closed at both ends and having a bottom wall inclined from one end toward the other end of the receptacle, and a member adjustably secured to the receptacle and adapted for engagement about a patient's ear, the end of the receptacle at the lower end of said bottom wall being adapted for coaction with said member for securing the device in position adjacent to

and extending outwardly from the patient's ear.

4. In a device of the character described, a troughlike receptacle having its bottom wall inclined from its outer end to its inner end, said receptacle being closed at both ends, and a bail adjustably secured to the receptacle adjacent to the inner end thereof and adapted for engagement over a patient's ear, the inner end wall of the receptacle being cut away to fit about the lower portion of the patient's ear and to co-operate with said bail for holding the receptacle in position.

In testimony whereof we affix our signatures.

FREDERICK A. DAVIES.
CARL L. ROGERS.
